UNITED STATES PATENT OFFICE.

RALPH H. KINGDON, OF CHICAGO, ILLINOIS, ASSIGNOR TO SEARS, ROEBUCK AND CO., OF CHICAGO, ILLINOIS, A CORPORATION OF NEW YORK.

IMPACT-CUSHIONING DEVICE.

Application filed May 16, 1921. Serial No. 470,041.

To all whom it may concern:

Be it known that I, RALPH H. KINGDON, a citizen of the United States, residing at Chicago, in the county of Cook and State of Illinois, have invented certain new and useful Improvements in Impact-Cushioning Devices, of which the following is a specification.

This invention relates to impact cushioning devices for closures such as windows, doors and the like, and is particularly concerned with the provision of a device of this kind which is especially adapted for use with automatically operable windows and similar contrivances.

One of the principal objects of the invention is to provide such a device which will operate entirely automatically without any especial adjustment or attention and which is so constituted that the impact will not be cushioned when the window closes rather slowly and with comparatively slight momentum but which will operate with certainty to cushion the impact when the window closes with comparatively great momentum, that is when considerable noise, besides damage to the sash might otherwise result.

Another object of the invention is to provide a device of this character which may be installed in a window casing of standard construction without necessitating any considerable reconstruction of the casing.

Other objects, advantages and uses of this cushioning device will appear as the following detailed description progresses which is to be read in connection with the accompanying drawings wherein—

Fig. 1 is a front elevation of a window equipped with a device constructed in accordance with this invention for cushioning the impact of the sash with the casing. The casing is broken away at one point to reveal more clearly the manner of attaching the device to the casing.

Fig. 2 is a central, longitudinal, vertical section of the device, the elements of which are shown in their respective inoperative positions.

Fig. 3 is a similar section wherein the parts are illustrated in operative position.

Fig. 4 is a transverse, vertical section taken on lines 4—4 of Figs. 2 and 3 looking in the direction indicated by the arrows.

Figs. 5, 6, 7 and 8 are perspective details of one-half of the casing, the spring frame

member with spring attached, a locking dog and the inertia operable dog actuating plate respectively.

The same reference numerals are applied to corresponding parts throughout the views.

Referring to the drawings, and for the present to Fig. 1 particularly, reference numeral 10 represents a window casing comprising a frame 11 and face boards 12. Movable between the usual beads in the casing 10 is a sash 13 in connection with which the impact cushioning device of the present invention is adapted to operate.

The reference numeral 14 is applied to the cushioning device as a whole. It consists of a two-piece metal casing 15 made up of the halves 15^a which are reversible and interchangeable. A closure 16 in the form of a thin sheet metal strip overlies the edges of an opening 17 cut into the upper cross piece of the frame to receive the casing 15. This closure is fastened to the nether side of the cross piece by screws 18 which are received in screw holes in the lugs 19 on the halves 15^a. These lugs, as most clearly shown in Fig. 5, project from opposite ends of the halves 15^a and are notched as shown, the notches when the halves are placed in register, forming screw holes to receive the screws 18. The closure seals the lower open end of the casing 15 and has a central opening 20 to receive a coiled compression spring 21.

A bolt 22 passing through a collar 23 and a channel or trough-shaped frame 24 receives a nut 25. The collar 23 has an over-turned edge which embraces the end of the spring 21 and secures the same to the frame 24. If desired the spring may be sweated in the collar to secure a permanent connection therewith. The frame 24 is reciprocable in the casing 15 and is preferably maintained by gravity, normally in the position shown in Fig. 2 at the lower end of the casing in engagement with the closure 16.

A pair of locking dogs 26 are pivotally mounted in the frame 24 on pins 27 which pass through the spaced ears 28 of the dogs and are received in openings in the parallel side walls of the frame. A leaf spring 29 flexed over the pins 27 and engaging the lower edges of the dogs between the ears 28 thereof, serves to hold them upwardly

and together out of the path of abutments 30 which are formed on the inner end walls of the casing halves 15^a as most clearly shown in Fig. 5. Openings 31 serving as 5 air vents are provided in the walls of the casing beneath the abutments. These openings afford in addition freedom of motion for the dogs 26.

A rectangular plate 32 rests upon the ears 10 28 of the dogs and is notched at its corners as shown at 33 in Fig. 8 to center the plate and prevent displacement thereof from the dogs when they occupy the position shown 15 in Fig. 3. The plate 32 is comparatively large and heavy relative to the dogs and normally is held lightly in raised position by the leaf spring 29.

When the spring 21 is suddenly struck by 20 the window, in closing, the plate 32 due to its comparatively greater mass tends to remain at rest and so by its inertia exerts a sudden increased pressure on the dogs 26 sufficient to counteract the action of the spring 29 which then becomes flexed, as 25 shown in Fig. 3. The dogs are forced outwardly into the path of the abutments 30 with which they engage and prevent movement of the frame 24 farther upwardly into the casing 15. The spring 21 still projects 30 downwardly a substantial distance from the top of the window casing and upon further movement of the sash is compressed, thereby exerting a constantly increasing counter-force which, when the force of the impact 35 is spent and the sash comes to rest, is ample to move the sash downwardly as the spring expands. Upon the subsequent return of the sash, that is, when the spring 21 is no longer compressed, the dogs are no longer 40 held in engagement with the abutments sufficiently to prevent the spring 29 moving them inwardly out of the path of the abutments. The dogs therefore are retracted and upon the return of the window permit 45 the same to close. The window moving comparatively slowly, simply pushes the spring 21, frame 24 and members therein upwardly before it into the casing 15 substantially to the dotted line position indicated in Fig. 2. The action of the cushioning device is the same where the window, 50 due to any cause, closes slowly.

Where the device is utilized in connection 55 with doors or other closures or where it must necessarily lie in a horizontal plane, the frame with its dogs and actuating plate cannot, of course, be held in outermost position by gravity. In this construction I contemplate using springs or other means suitable, for the purpose. The spring taking the place of gravity would be lighter than the leaf spring 29 for obvious reasons.

If desired, a pin 34 may be provided extending over the plate 32 and held in the 60 parallel side wall of the frame 24 to pre-

vent possible displacement of the plate 32. It will be understood that this pin is by no means an absolutely essential provision inasmuch as there will be no considerable 70 tendency for the plate to be projected upwardly out of the frame 24 when the frame 24 is locked in position by the locking dogs 26. This is due partly to the action of gravity effective even after the inertia of the plate has been overcome and partly also to 75 a rather slight plunger action noticeable when the frame is moved rapidly upwardly. The air above the frame, it will be seen, has a restricted passage through the openings 31 and around the edges of the frame 80 24. The plunger action of the plate 32 assists considerably too in actuating the dogs 26 in the manner referred to above.

The invention finds application on any 85 type or kind of window and is, of course, applicable wherever two objects of any kind are arranged to impact. However, I prefer to utilize the device in connection with an automatically operable window in which connection it is especially useful.

Referring to Fig. 1, the weights 35 preferably overweight the window so that the sash 13 normally tends to move upwardly to closed position. Any kind or form of 95 mechanism may be used to hold the window stationary in its adjusted position. Such a mechanism is diagrammatically illustrated at 36 and is preferably, although not essentially, controlled by a clock 37. A mechanism especially suitable for this purpose 100 is described and claimed in Patent No. 1,485,578, issued March 4, 1924, to Lee E. Wolgemuth.

It will, of course, appear from the foregoing description that when the window, 105 due to warped beads, excessive friction, or any other cause moves rather slowly and with comparatively slight momentum, the locking dogs will not be projected outwardly into the path of the abutments when the window engages the spring 21. Under such circumstances no noise could be occasioned by the closing of the window nor is there any likelihood that the sash would be damaged, so that it is quite practical that the 110 window is permitted to close without any interruption.

My invention finds wide application and is of course capable of considerable modification in its details so that it will be understood that I in nowise limit my invention to the specific constructions and arrangements herein described but cover all legitimate modifications, adaptations and embodiments coming within the spirit and scope 115 of the appended claims.

I claim as my invention:

1. The combination with an overweighted window arranged normally to move in its casing to closed position under propulsion 120

of its weights, of means for cushioning the impact of said window with said casing operable when said window closes with a given momentum and inoperable to cushion 5 the impact of closing at a lesser momentum, comprising a compression spring, a channel frame secured to an end thereof, said frame being movable inwardly and outwardly in a socket provided in said casing and nor- 10 mally held in its outermost position by gravity, a pair of dogs pivotally mounted in said frame, abutments in said socket adapted to be engaged by said dogs, spring means tend- 15 ing to hold said dogs together out of the path of said abutments and means adapted to repel said dogs and cause engagement thereof with said abutments comprising a plate operable by its inertia and by plunger action in said socket when said window en- 20 gages and moves said frame inwardly with a given momentum, said repelling means being inoperable to cause locking engagement of said dogs when said window moves to closed position with comparatively slight 25 momentum.

2. The combination with a casing and a closure therefor adapted normally to move to a position at one end of said casing, of means for cushioning the impact of said 30 closure with said casing operable when said closure impacts with a given momentum and inoperable to cushion the impact at a lesser momentum, comprising a frame movable in a socket provided in said casing and 35 normally held in its outermost position, a spring on said frame adapted to project into the path of said closure, dogs in said frame, abutments for said dogs, means tending to hold said dogs out of the path of said abut- 40 ments and means adapted to repel said dogs and cause engagement thereof with said abut- 45 ments comprising a plate operable by its inertia when said closure engages its casing with a given momentum, said plate being inoperable to cause locking engagement of said dogs at a lesser momentum.

3. The combination with a casing and a closure therefor adapted normally to move to a position at one end of said casing, of 50 means for cushioning the impact of said closure with said casing, comprising a frame movable in a socket provided in said casing, a spring on said frame, dogs in said frame, abutments for said dogs, and means adapt- 55 ed to repel said dogs and cause engagement thereof with said abutments.

4. The combination with members adapt- 60 ed to move into abutting relation, of means for cushioning the impact of said members when they engage with comparatively consider- 65 able momentum, said means being incapable of cushioning the impact of said members when they engage with comparatively slight momentum.

5. The combination with a casing, a clo-

sure adapted to move toward and engage a side of said casing, means interposed between said closure and casing to cushion the impact thereof, said means being adapted to cushion the impact upon initial engagement 70 of said closure with its casing, to cause a recoil of said closure, and thereupon to yield upon the return of said closure and move before said closure into a socket provided therefor in said casing to be inoperable fur- 75 ther as a cushioning element so long as said closure remains in engagement with said casing.

6. The combination with a casing and a member movable to close said casing, of a cushioning device adapted to cause a recoil of said movable member without contact with said casing when said movable member approaches its closed position at more than a predetermined rate, said cushioning device being also adapted to yield and permit closure of said casing when said movable member approaches its closed position at less than said predetermined rate.

7. The combination with a stationary member and a relatively movable second member steadily impelled toward said stationary member and adapted to engage therewith, of means common to said members adapted to cushion the impact thereof comprising a yielding element, a support therefor, said support having a socket adapted to receive said yielding element, means in said socket adapted to constitute a rigid abutment for said yielding element when said movable second member approaches said stationary member with comparatively great momentum whereby engagement of said members is prevented, said last mentioned means being adapted to re- 90cede with said yielding element into said socket when said second member approaches the first member with comparatively slight momentum to permit the same to engage 95 without cushioning the impact.

8. The combination with a stationary member and a second member adapted to engage therewith, of means adapted to cushion the impact thereof comprising a yielding element, means adapted to constitute a rigid abutment for said yielding element when said second member approaches said first mentioned means rapidly thereby preventing engagement of said members, said first mentioned means being adapted 100 to recede with said yielding element to permit said members to engage without cushioning the impact.

9. The combination with a first member and a movable member adapted to engage therewith, of means common to said members adapted to cushion the impact thereof, comprising a cushioning element, and means adapted to constitute a rigid abut- 105 ment for said cushioning element when said 110 cushioning element is engaged by said movable member.

movable member approaches with comparatively great momentum thereby preventing engagement of said members, said means being adapted to permit said members to engage and being inoperative to cushion the impact thereof when said movable member approaches with comparatively slight momentum.

10. The combination with two members 10 adapted to engage with considerable momentum gained as said members move relatively together, of cushioning means common to said members adapted upon initial engagement of said members to cause a recoil thereof without impact when the rate of approach of said members exceeds a predetermined amount, said cushioning means being adapted to move to a position from between said members to permit the same 20 to engage when the rate of approach is less than said predetermined amount.

11. The combination with two members adapted to engage, of means adapted to cushion the impact and cause a recoil 25 thereof upon initial engagement and adapted thereupon when the force of the impact is spent to yield to permit movement of the members to engagement.

12. A cushioning device comprising, in 30 combination, a casing, a frame received in said casing and adapted to have movement inwardly and outwardly as a plunger therein, said frame being held normally in outermost position by gravity, a cushioning 35 element mounted on said frame and projecting without said casing and means in said casing adapted to hold said frame stationary when said cushioning element impacts with an object and adapted to permit 40 said frame to move when the force of said impact is comparatively slight, comprising an abutment in said socket, a dog pivotally mounted in said frame adapted to engage said abutment to hold said frame stationary 45 and prevent inward movement thereof, spring means normally holding said dog out of the path of said abutment and means operable by its inertia and by plunger action in said socket to actuate said dog.

50. 13. A cushioning device comprising, in combination, a casing, a frame reciprocable in said casing and held normally in outermost position, a cushioning element on said

frame and means adapted as a stop for said frame when said cushioning element impacts 55 with said frame at a relatively high velocity and adapted to permit the uninterrupted movement of said frame when the force of said impact is comparatively slight, comprising an abutment, a dog adapted to engage said abutment, means normally holding said dog out of the path of said abutment, and means operable by its inertia to actuate said dog.

14. A cushioning device of the character 65 described comprising, in combination, a frame reciprocable in a socket and held normally in its outermost position, a cushioning element on said frame and means adapted as a stop for said frame when said cushioning element suddenly impacts therewith, said means comprising an abutment in said 70 socket, a dog adapted to engage said abutment, means normally holding said dog out of the path of said abutment and means for 75 actuating said dog.

15. A cushioning device of the character described comprising, in combination, a cushioning element disposed in a socket, and means adapted to constitute a stop for said 80 element when it suddenly impacts with an object, comprising an abutment, and means adapted to engage said abutment, said means being operable only when the object impacts 85 with said cushioning element with a predetermined momentum.

16. A device of the character described, comprising a casing, a frame movable as a plunger in said casing normally held at one side thereof by gravity, a cushioning spring 90 projecting through an opening in said casing adjacent said frame and secured to the outer side of said frame and devices for holding said frame stationary to act as a stop for said cushioning spring when the same is suddenly engaged by an object comprising an inertia operable dog pivotally mounted in said frame and an abutment in said casing 95 adapted to be engaged by said dog, said devices being operable only when said cushioning spring is engaged with a predetermined momentum.

In testimony whereof, I have hereunto set my hand.

RALPH H. KINGDON.
